UNITED STATES PATENT OFFICE.

EMIL WAGENER, OF DAHLHAUSEN-ON-THE-RUHR, GERMANY.

PROCESS OF REMOVING TAR IN RECOVERING AMMONIA.

977,909.

Specification of Letters Patent.

Patented Dec. 6, 1910.

Application filed November 9, 1909. Serial No. 526,947.

To all whom it may concern:

Be it known that I, EMIL WAGENER, a subject of the King of Prussia, Emperor of Germany, and a resident of Dahlhausen-on-the-Ruhr, Westphalia, Kingdom of Prussia, Germany, have invented certain new and useful Improvements in Processes of Removing Tar in Recovering Ammonia, of which the following is a specification.

10 In the production of sulfate of ammonia by directly introducing the hot distillation gases, freed from the greater portion of their tar, into the saturator, difficulty has been experienced owing to the fact that in 15 the acid bath small quantities of tar are separated and collect on the surface. If this tar is not removed it becomes resinous, mixes with the precipitating salt and gives to the same a dirty appearance. It is therefore 20 important to provide for a constant removal of those quantities of tar even though they are small.

The present process has for its object to 25 constantly remove this tar and includes the further purpose of continuously renewing the surface of the bath in the saturator. To this end the gas, containing slight traces of tar, as previously stated, is passed over the 30 surface of the acid bath and the tar carried by it, and which collects on the surface of said bath, is carried to the periphery of the bath by the action of the moving current of gas, whence this tar escapes through an overflow connection. It necessarily occurs that 35 with the small quantity of tar escaping through the said overflow, larger quantities of lye are carried off and this lye is returned into the saturator near the surface in a strong stream after the elimination of the tar. By 40 this proceeding a constant renewal of the liquid occurs at the surface besides the complete separation of tar; furthermore the surface is maintained in continuous motion by the strong influx and reflux of the liquid. 45 The tar therefore is completely carried off and the washing liquid is continuously renewed so that even in case of rapid evaporation changes of the level of the liquid within the bath cannot occur.

50 In the accompanying drawing the apparatus is represented which serves for carrying out the process.

The drawing shows in Figure 1 partly a vertical section, partly an elevation, in Fig. 55 2 a plan view of the apparatus.

The saturator 1 having a gas inlet pipe 2 and two gas outlet connections 3 is provided with an overflow connection 4, to which the discharge pipe 5 is connected. Said pipe 5 dips into the separating vessel 6 which is divided into two compartments 8, 9 by a partition 7, the compartments communicating with each other beneath the partition. Through the dipping pipe 5 a mixture of tar and lye flows off; the tar of lighter specific weight is separated within the vessel 6 by rising toward the surface and is removed by ladling it out or it flows off through overflow pipe 10 into the vessel 11. The lye passes below the partition 7 into the compartment 9 and flows by tube 12 into the vessel 13 from which it is returned in a strong stream, through pipe 15, by means of the ejector 14 operated by steam or compressed air supplied through pipe 16, into 75 the saturator near the surface of the liquid thefein.

What I claim is:—

1. The process for producing sulfate of ammonia from gases resulting from the distillation of coal and the like, which consists in passing the said gases into proximity to an acid bath, drawing off from the surface of said bath tar which collects thereon together with the surface portion of the liquid of the bath, separating the tar so drawn off from the liquid drawn off with it, and returning said liquid to the bath, the surface of the bath being thereby constantly renewed.

2. The process for producing sulfate of ammonia from gases resulting from the distillation of coal and the like, which consists in passing the said gases into proximity to an acid bath, drawing off from the surface of said bath tar which collects thereon together with the surface portion of the liquid of the bath, separating the tar so drawn off from the liquid drawn off with it, and returning said liquid to the bath, near the surface of the bath, the surface of the bath being thereby constantly renewed by the outflow and inflow of such liquid.

In testimony whereof I have signed this specification in the presence of two subscribing witnesses.

EMIL WAGENER.
